UNITED STATES PATENT OFFICE.

HENRY H. DUPONT, OF INDIANAPOLIS, INDIANA.

CONCRETE FLOORING.

1,081,373.

Specification of Letters Patent.

Patented Dec. 16, 1913.

Application filed May 26, 1910. Serial No. 563,516.

To all whom it may concern:

Be it known that I, HENRY H. DUPONT, of Indianapolis, county of Marion, and State of Indiana, have invented a certain 5 new and useful Concrete Flooring; and I do hereby declare that the following is a full, clear, and exact description thereof, reference being had to the accompanying drawings.

10 The object of this invention is to improve the construction of reinforced concrete flooring and similar structures.

One feature of the invention consists in making a reinforced concrete flooring or 15 the like of previously formed sections or beams made of concrete combined with skeleton tiles. These sections or beams, after having been previously formed, are placed side by side in the flooring and their 20 adjacent sides interlocked with subsequently added concrete filling. These concrete beams are provided with triangularly disposed reinforcing wires embedded midway between the sides and with their upper an- 25 gles projecting above the beams so as to form a row for the full length of the beam. These wires are tied to a reinforcing rod embedded in the beam and enable the beam to be engaged by hoisting apparatus for 30 lifting it into place and also project into the concrete filling which is added or laid upon said beams after they are put in place in the flooring.

Combined with the foregoing is the fur- 35 ther feature of wooden stringers being em- bedded in the concrete interlocking filling between each pair of beams and through which nails or the like extend transversely for holding the stringers in place, whereby 40 wooden flooring may be laid if desired.

The nature of this invention will be un- 45 derstood from the following description and claim and the accompanying drawings.

In the drawings Figure 1 is a perspective 50 view of a concrete beam or section after it is formed and placed in the flooring with the hoisting chain attached. Fig. 2 is a central longitudinal section through a portion of said beam. Fig. 3 is a transverse vertical section through a portion of the 55 flooring with concrete flooring laid. Fig. 4 is the same with wooden flooring laid.

The flooring is formed of concrete beams, like that shown in Figs. 1 and 2, associated 60 together substantially as shown in Figs. 3 and 4, with a suitable flooring surface add-

ed on top and plastering added below. The beams are previously formed and consist of two series of similarly formed hollow or skeleton tiles 10 placed beside each other with intervening filling 11 of concrete. These tiles have their inner portions relatively thin as compared with their outer portions, which, when placed together for receiving the concrete, form a trough-like 65 concavity. Along the upper corners of the tiles there are longitudinally extending dove-tailed recesses 12 which form in the finished beam continuous grooves.

In the concrete filling in each beam there 70 is a continuous reinforcing rod 13 near the bottom with an eye 14 at each end. From this rod A-shaped wires 15 extend upwardly above the surface of the concrete, said wires being first secured to the rod 13 and then bent upwardly above the concrete and again wrapped around the rod 13. This is continuous throughout the length of the beam so they present a row of A-shaped projections above the concrete, as seen in Fig. 1. 75 Oblique reinforcing rods 16 are connected with the rod 13 between its ends and extend at an inclination through the concrete to and beyond the end near the upper surface and have eyes 14 at their outer ends. These 80 beams are lifted by suitable hoisting apparatus having chains 20 with hooks on the ends adapted to catch in the wires 15 to the position in the flooring with the ends of the beams resting upon suitable beams in 85 the frame work of the building or general structure. These beams are placed side by side, as shown in Figs. 3 and 4, and form a continuous unbroken surface on the under- 90 side for the ceiling 21.

95 After the beams above described are laid, a concrete filling 22 is spread over the same so as to extend above the reinforcing wires 15. The floor is strengthened by the pro- 100 jection of the wires 15 into its upper con- crete filling. The adjacent beams are locked together by reason of the concrete filling 22, filling the two dove-tailed grooves 12 in the adjacent beams, as shown at 24 in Figs. 3 and 4. The concrete also fills a space be- 105 tween the lower portions of each pair of beams. This makes a very firm and strong flooring construction. The upper floor sur- 110 face may be made of concrete 25 spread upon the filling 22, or it may be a wood, 115 flooring 26 laid upon the concrete filling 22 and nailed down to the wooden stringers

27, which are embedded between each pair of beams and in the concrete filling 22 in the grooves 12. If desired, nails 28, or the like, are driven transversely through the stringers 27, so that the ends will project into the concrete filling 24 and further strengthen the structure.

What I claim as my invention and desire to secure by Letters Patent is:

10 A concrete beam consisting of an opposing series of tiles that constitute the sides and bottom of the beam and longitudinally recessed upon their upper sides to form a

space between them, concrete filled in between said series of tiles, a rod embedded 15 longitudinally in the lower part of said concrete, and a wire connected with said rod at intervals and having looped projections which extend above the concrete.

In witness whereof, I have hereunto affixed my signature in the presence of the witnesses herein named.

HENRY H. DUPONT.
